(57) **CLAIM**

The ornamental design for an illuminated tweezers, as shown and described.

DESCRIPTION

FIG. 1 is a front perspective view of the illuminated tweezers showing my new design;

FIG. 2 is a front view of the illuminated tweezers;

FIG. 3 is a left side view of the illuminated tweezers thereof;

FIG. 4 is a rear view of the illuminated tweezers thereof;

FIG. 5 is a right side view of the illuminated tweezers thereof;

FIG. 6 is a top end view of the illuminated tweezers thereof;

FIG. 7 is a bottom end view of the illuminated tweezers thereof; and,

FIG. 8 is a front perspective view of the illuminated tweezers with a cover.

The broken lines shown at the ends of the tweezers' tips represent the bounds of the claim. All other broken lines illustrate portions of the article. None of the broken lines form a part of the claimed design.
